UNITED STATES PATENT OFFICE

2,372,718

DESK WITH TYPEWRITER CARRIER.

Martin Fox, Chicago, Ill., assignor to The Seng Company, a corporation of Illinois

Application November 29, 1943, Serial No. 512,096

7 Claims. (Cl. 312—29)

This invention relates to office desks having a typewriter compartment and provided with a carrier for moving the typewriter from a vertically depending position to an extended raised horizontal position at one side of the desk.

The present invention provides certain improvements for the device shown in my Patent No. 2,214,526, issued September 10, 1940.

In office desks of this general character, it is customary to have the typewriter compartment at one side of the desk spaced from a bank of drawers at the other side, the compartment being provided with a door and having a carrier for supporting the typewriter suspended within the compartment. The typewriter is usually fixed to a platform which is hinged to a slide member so that it may be rolled into and out of the compartment. When extended and raised to a horizontal position, the platform is gripped in that position to provide a firm writing support.

The primary object of the present invention is to provide improved means for holding the typewriter platform in extended horizontal position, so that it will be clamped firmly to the desk and will not rattle during the operation of the typewriter.

A further object of the invention is to provide a strong channel-like slide which carries the typewriter platform, and to support the slide so that it will not be distorted by the weight of a typewriter fixed to the platform.

Another object of the invention is to provide an improved latch for locking the platform in depending vertical position on the slide when the typewriter is rolled back into the compartment, and to provide automatic means for releasing the lock when the slide is fully extended from the compartment.

The invention is illustrated in a preferred embodiment in the accompanying drawings, in which—

Figure 1 is a fragmentary plan view with the desk top removed, taken as indicated at line 1—1 of Figure 2, and showing apparatus embodying the invention with the typewriter platform in extended horizontal position; Figure 2, a fragmentary vertical sectional view, taken as indicated at line 2—2 of Figure 1; Figure 3, a fragmentary front elevational view of the apparatus shown in Figures 1 and 2 with dotted lines indicating the depending vertical position of the typewriter which it assumes when in the typewriter compartment; Figure 4, an enlarged fragmentary sectional view, taken as indicated at line 4—4 of Figure 3; Figure 5, a fragmentary vertical sec-

tional view, taken as indicated at line 5—5 of Figure 4; and Figure 6, an enlarged fragmentary sectional view, similar to Figure 5 with the counterbalancing mechanism removed to show the clamping device.

In the embodiment illustrated, an office desk 1 is provided with a compartment 8 to house a typewriter. A suitable door, not shown, may be provided for the front end of the compartment to complete the closure when the typewriter is not in use. Preferably, one side wall of the compartment is provided with a fixed longitudinally extending bar 9 on which the carrier is mounted and a parallel bar 10 affords a track for a roller on the lower end of the carrier.

At the front end of the compartment, a fixture 11 is firmly secured to the bar 9 and is provided with anti-friction rollers 12 to receive the channel-like slide member 13. As best shown in Figures 1 and 2, an upwardly extending track 14 is mounted on the bar 9 and its inner face provides a track for a top roller 15. If desired, the member 14 may be formed integrally with the fixture 11.

The slide member 13 is provided near its rear end with an upwardly extending standard 16 to brace the slide member and prevent its distortion when the assembly is retracted into the compartment. The upper end of the standard has an extension 17 which provides a journal for the roller 15 and the lower end of the standard has an extension 18 to provide a journal for the anti-friction roller 19.

A typewriter platform 20 is hinged to the slide member 13, as indicated at 21, and has near its free end an upwardly extending bracket 22 which affords an adjustable anchorage 23 for a counterbalancing torsion spring 24 which is secured at its other end to the standard 16.

As shown in Figure 5, the underside of the platform is provided with a catch 25 to be engaged by a latch 26 which is pivoted to the standard 16 at 27 and is urged into latching position by spring 28. As best shown in Figures 4 and 5, the latch is provided with a lug 29 which limits the movement of the latch under the influence of the spring 28 by engagement with the standard 16. The latch also has an upwardly extending arm 30 which will engage a stop 31 secured to the side wall of the compartment 8 beneath the fixture 11.

Thus it will be understood that when the slide member 13 is fully extended to the position shown in Figure 4, the latch is automatically released and the typewriter platform 20 is free to swing

upwardly to horizontal position under the influence of the counterbalancing spring 24. In returning the typewriter into the compartment, the typewriter platform is held in vertically depending position until the platform has been moved rearwardly a sufficient distance to clear the stop 31 and permit the latch to automatically reengage.

It will be seen that when the typewriter is moved back into retracted position in the compartment, it has a tendency to exert a torsional movement on the slide member 13 which is supported on the fixture 11. However, the rollers 15 and 19 on the standard 16 resist this torsional strain and permit the slide to operate very easily.

As shown in Figure 4, the doorway to the typewriter compartment is provided with a crosspiece or lintel 32 which is provided with a groove 33. The typewriter platform 20 is provided with a fixed upstanding cross-bar 34 which has at its top edge a tongue 35 to engage the groove 33 when the platform is moved to horizontal position. As pointed out in my Patent No. 2,214,526 this type of connection helps to eliminate lateral movement and vibration of the platform. However, in the present application, an improved clamping mechanism is provided.

A stud 36 is firmly secured to the lintel 32 by a bracket 37. As best shown in Figure 6, a bracket 38 is fixed to the platform 20 and is provided with a groove-like seat 39 to receive the stud 36 when the platform is moved to horizontal position. A hook-like latch member 40 is urged into latching engagement with the stud by means of a spring 41. The latch member is impaled by a rod 42 which has its rear end 43 bent upwardly and welded to the latch 40. The rod makes a pivotal connection with the bracket 38 and extends through the member 34 and is turned, as shown at 44, to provide an operating handle. Thus it will be seen that when the platform 20 is swung to extended horizontal position, the hook 40 will snap over the stud 36, and by pushing the handle 44 downwardly, the stud will be gripped against the seat in the bracket 38 and the platform will be gripped very firmly to the desk.

It will be understood that a typewriter may be firmly attached by screws to the platform 20 and the tension in the spring 24 adjusted to counterbalance its weight. To return the typewriter to the compartment from writing position, it is merely necessary to lift the handle 44 upwardly, swing the typewriter down and hold it in depending vertical position while pushing it into the compartment enough to permit the latch 26 to engage. The typewriter will then be locked in vertical position and it may be retracted into the compartment.

The foregoing detailed description has been given for clearness of understanding only, and no unnecessary limitations should be understood therefrom for some modifications will be obvious to those skilled in the art.

I claim:

1. In a desk having a typewriter compartment: a metal supporting fixture fixed in the front of said compartment and provided with spaced roll-

ers; a channel member slidably mounted for longitudinal horizontal movement on said fixture, said channel member having at its rear end a standard provided at its lower end with a roller adapted to ride on the inner wall of the compartment and at its upper end with a roller positioned to ride on the outer surface of a vertically extending horizontal track; a typewriter platform hinged to the front portion of said channel member to swing laterally from a depending vertical position to a horizontal writing position; a catch on the platform; and a pivotal spring latch on the lower portion of said standard to engage said catch and secure the platform in depending position, said latch having an arm to engage a stop fixed to the desk and automatically disengage the latch when the channel member is extended from said compartment.

2. Apparatus as specified in claim 1, including releasable means on the typewriter platform for clamping said platform firmly to the desk when the platform is in extended horizontal position.

3. In a desk having a typewriter compartment provided with a forwardly extending slide on which a typewriter platform is hingedly mounted, means for releasably clamping said platform to the front of said desk when in extended horizontal position comprising a stud on one of the members and a pivotally mounted hook provided with a manually operable crank on the other member, said hook having an inner cam-like surface to grip said stud and draw said members together rigidly.

4. In a desk having a typewriter compartment provided at its upper open end with a downwardly grooved crosspiece; a typewriter platform hinged to an extensible slide mounted in said compartment, said platform having near its rear edge a tongue to engage said grooved crosspiece when the platform is extended and swung to horizontal position; and means for clamping said platform to the crosspiece including a stud fixed to the desk, and an oscillatable hook on said platform having an inner cam-like surface to grip said stud and draw the platform upwardly.

5. A device as specified in claim 4, in which the platform has a fixed upwardly extending seat to receive the stud when it is gripped.

6. In a desk having a typewriter compartment provided with a forwardly extending slide on which a typewriter platform is hingedly mounted, means for releasably latching said platform in vertical depending position on said slide; means for automatically releasing said latching means when the slide is extended; and manually operable means for clamping the platform to said desk when said platform is moved to extended horizontal position.

7. A device as specified in claim 6, in which the manually operable clamping means includes a rearwardly extending stud fixedly mounted in the upper front portion of the typewriter compartment, and the platform has a hook latch to engage said stud and draw said platform upwardly.

MARTIN FOX.
